UNITED STATES PATENT OFFICE

IRVING R. HIPPENMEYER, OF WAUKESHA, WISCONSIN, ASSIGNOR TO THE CREAMERY PACKAGE MFG. COMPANY, OF CHICAGO, ILLINOIS, A CORPORATION OF ILLINOIS

PRERINSING DEVICE FOR BOTTLE WASHERS

Application filed December 10, 1927. Serial No. 239,090.

The invention relates to bottle washing apparatus, more particularly to a device for subjecting bottles to a preliminary rinsing before being subjected to the cleansing treatment.

The invention is particularly adapted to a bottle washing machine of the type represented in Patent No. 1,749,989, granted March 11, 1930, upon the application of George F. Soelch, and while not limited to use with that machine the invention is herein illustrated and described for convenience as a part of or attachment for the machine set forth in the above mentioned application.

Bottle washing machines of the type mentioned comprise an endless conveyor carrying rows of bottle pockets in which the bottles are deposited and are thereby carried through successive compartments in the machine for soaking treatment by submergence in cleansing solution contained in tanks, the bottles being subsequently subjected to spraying and rinsing treatment. Empty bottles returned to dairy plants from milk consumers frequently contain foreign matter and are in such soiled condition that if the bottles were at once introduced into the solution tanks the solution therein would quickly become seriously fouled and greatly reduced in effectiveness.

To avoid this result it is obviously desirable to give the soiled bottles a preliminary rinsing for the removal of the greater portion of such soil and its diversion from the solution tanks before the bottles enter the latter.

It is the principal object of this invention to provide means for subjecting bottles to a pre-rinsing spray in machines of the type mentioned, with provision for carrying the discharged rinse water away from the usual cleansing solutions.

Another object is to provide such a pre-rinsing means in connection with an automatic loading device for depositing bottles after such rinsing in the conveyor pockets as the latter progress by the loading station.

Another object is to provide automatic means for stopping the operation of the machine in case bottles passing from the pre-rinsing device to the conveyor pockets fail

of full normal movement thereinto, and thus prevent jamming of the bottles and damage to the machine.

A further object is to provide an automatically interposed stop for arresting bottles within a rinsing chamber, with which stop is associated spraying means for rinsing the bottles, the stop being withdrawn automatically after rinsing to permit the bottles to pass into the conveyor pockets.

A further object is to provide means for adjusting the position of the rinsing chambers so that the latter may be accurately aligned with the conveyor bottle pockets as the latter are positioned for receiving the bottles.

Other objects and advantages will be apparent in the following detailed description of a preferred embodiment of the invention which has been selected for illustration in the accompanying drawings. It will be understood, however, that various changes in form and arrangement may be made by those skilled in the art without departing from the spirit and scope of the invention as expressed in the appended claims.

Referring to the drawings:

Figure 1 illustrates in side elevation a fractional portion of the end of a bottle washing machine similar in structure to that illustrated in the before mentioned copending application, and with which is incorporated the invention herein disclosed.

Fig. 2 is a cross sectional view in elevation taken on the plane of the line 2-2 in Figure 1.

Fig. 3 is a longitudinal section of a view in elevation taken on the plane of the line 3-3 in Fig. 2.

Figs. 4 and 5 respectively illustrate in vertical section the bottle stop and spraying mechanism in its two operative positions.

Fig. 6 is a detailed view of fractional end portions of the bottle stop and spraying mechanism.

Fig. 7 illustrates the spray supply pipe connection, and the automatic valve control therefor.

Referring to Fig. 1 the numeral 1 indicates a power driven shaft which is the prime actuating element in a Geneva transmission.

of conventional structure comprising the disk 2, the crank 3 carrying the actuating pin 4 and the slotted star wheel 5 mounted on the shaft 6.

5 The intermittently driven shaft 6, extending transversely through the washing machine, is in driving engagement with a pair of sprockets in a series of which one is indicated at 7 in Fig. 3, the series of sprockets operatively supporting a parallel pair of endless conveyor chains of which one is indicated at 8. The chains 8 carry at spaced intervals transversely arranged groups of bottle pockets 9 within which the bottles are deposited, 10 as hereinafter described, to be subjected to the washing treatment. The endless conveyor and its series of bottle pockets are moved intermittently through the several stations provided in the machine for the cleansing treatment, the intermittent movement being accomplished by the Geneva device illustrated in Fig. 1.

15 The foregoing structure is fully described and illustrated in complete detail in the aforementioned patent, and not being a part of the present invention is not further described herein. It will be understood that in the operation of the bottle conveyor the individual transverse groups of spaced bottle pockets are 20 successively brought to the position illustrated at A in Fig. 3 and remain at that position during the interval of arrested movement.

25 Positioned above and in axial alignment with the conveyor pockets 9, when in the position illustrated at A, is a bottle holder 10 comprising a suitable outer wall structure within which is provided a transverse series of chambers 11, each of which is open at the top and bottom and each of which is 30 in register with one of the bottle pockets 9 carried by the conveyor. The chambers 11 are preferably formed by vertical partitions 12 and trough-like bottom wall 13 adapted to receive and guide the bottles introduced 35 into the chambers, as hereinafter described. 40 The bottle holder structure 10 is mainly supported by means of brackets 14 secured to the upper margin of the lower wall of the holder and having a loose bearing upon a 45 shaft 15 operatively supported in bearing brackets 16 secured upon the side walls of 50 the washing machine.

55 Accurate alignment of the chambers 11 with the bottle pockets 9 in their arrested position, as shown at A, is adjustably maintained by means of a threaded adjusting bar 17 rotatably secured in an oscillating block 18 provided with laterally extending pivot pins 19 having their bearing in a bracket 20 secured to the lower marginal portion of the under wall of the bottle holder 10. The adjusting bar 17 is in intermediate screw threaded engagement with a bearing collar 21 also having laterally extending pivot 60 studs 22 which have bearing support in a 65

bracket 23 stationarily secured to the end wall 24 of the washing machine. The adjusting bar 17 is provided with a hand wheel 25 at its outer end, by which the bar may be manually rotated to effect raising or lowering of 70 the lower end of the bottle holder to accurately register the latter with the bottle pockets in the conveyor.

75 Mounted in rigid relation to the shaft 15 is a rocking loading plate 26 upon which the bottles are placed by an operator while in the position indicated in Fig. 1, the plate being provided with trough-like supports 27 for individual bottles spaced similarly to the chambers 11 in the bottle holder, and 80 with an end wall 28 for retaining the bottles therein. The plate 26 is carried by a pair of brackets 29 rigidly secured to the shaft 15, and by the rotation of the latter the plate is elevated to the position represented in 85 dotted lines in Fig. 3, whereupon the bottles slide downward into the chambers 11 in the bottle holder.

90 The rock shaft 15 is operated by means of a crank 30 keyed to the outer end of the shaft and pivotally connected with a link bar 31 (Fig. 1) oppositely pivoted to a lever 32 having an intermediate fulcrum bearing upon a stationary stud 33 provided on a suitable bracket secured to the side wall of the 95 machine. The opposite end of the lever 32 extends into the path of movement of the pin 4 carried by the crank 3 mounted on the power shaft 1. The upper end of the lever 32 is of such form that its engagement by 100 the pin 4 effects the movement of the lever and of the rock shaft 15 so that the loading plate 26 is elevated to drop the bottles into the bottle holder chambers in synchronous time relation to the intermittent movement 105 of the conveyor bottle pockets into position A to receive the bottles.

110 This synchronous movement is obviously maintained by the association of the lever 32 with the Geneva transmission for the movement of the bottle conveyor. The return movement of the lever 32 may be adjustably limited by means of an adjustable stop provided for abutment by the lower end of the lever and comprising a stud 34 having screw 115 threaded support in a bracket 35 secured to the side wall of the machine, the stud having a conventional lock nut to secure it in the desired position.

120 A substantial space is provided between the adjacent ends of the bottle holder 10 and the bottle pockets 9 provided in the conveyor, wherein is operatively positioned an automatic bottle stop and pre-rinsing mechanism. The latter comprises a series of stop members 36 having segmental circular faces which are positioned respectively at the lower ends of the bottle chambers 11. The stop members 36 are operatively supported to be 125 swung upwardly across the open lower ends 130

of the bottle chambers 11, and in that position to provide abutments for the bottles discharged into the chambers from the loading plate 26. Each of the stop members is also provided with a spray jet from which a rinsing liquid is sprayed into the bottles while held in the bottle chambers, the stop members being then lowered and withdrawn from abutment with the ends of the bottles permitting the latter to slide over the stop members and into the bottle pockets of the conveyor.

As illustrated in Figs. 4, 5 and 6, each of the bottle stop and spraying members is provided with a segmental curved face preferably carrying a covering 37 of resilient material adapted to receive the bottles as they drop through the chambers 11, without damaging or chipping the abutting ends. The members 36 are secured to a supporting plate 38 extending transversely of the lower end of the bottle holder.

A tubular bar or pipe 39 extends through each of the stop members 36, the tube having a lateral opening within each of the stop members in communication with a passage terminating in a jet orifice 40 provided in the covering 37 and positioned for registry with the mouths of the bottles when in abutment with the stop member. A second supporting bar 41 extends parallel to the bar 39 and is secured in the lower portions of the stop members 36 to effect rigidity of the mounting of the series. The supporting tubes 39 and 41 are endwardly secured in a pair of swinging brackets 42 and 43, the latter being secured upon stub shafts 44 and 45 having bearing support in a pair of brackets 46 and 47 rigidly secured upon the opposite end walls of the holder 10.

The bracket 43 and stub shaft 45 are of hollow construction, providing a passage therethrough in communication with the tube 39 for supplying a rinsing fluid to the spray orifices in the stop members, the outer end of the hollow stub shaft 45 being connected through suitable flexible piping 46a with a pressure supply of rinsing fluid. The piping connections 46 are controlled by an intermittently operated valve 47a (see Fig. 7) which is positioned adjacent the main drive shaft 1. The latter carries a segmental cam 48 adapted to operatively engage the stem of the valve 47 during a portion of a revolution, whereby the spraying jets are operated to spray the bottles only when in upward position before the ends of the bottle chambers.

Mounted on the upper side of the supporting plate 38 is a series of trough-like structures 49 providing continuation of the chambers 11 for direction of the bottles from the latter into the bottle pockets when the stop members are withdrawn into lowermost position, the troughs 49 in effect bridging the

space between the bottle holder and the bottle pockets.

The stop members and their supporting structure are operatively moved into the respective positions described by means of a pair of cranks 50 mounted on the outer ends of the respective stub shafts 44 and 45 and pivotally connected respectively with a pair of links 51, which latter are pivotally connected to a pair of cranks 52 rigidly secured to the shaft 53 extending outwardly of and having its bearing support in the side wall of a washing machine.

Outwardly of the machine wall is an operating crank 54 (see Figs. 1 and 2) secured upon the shaft 53 and having a connecting rod 55 pivoted thereto, of which latter the opposite end is pivoted to one arm of a rocking lever 56 having intermediate bearing support upon a stub shaft 57, mounted upon the side wall of the machine. The opposite arm of the rocking lever 56 is operatively connected by means of a connecting link 58 with a bell crank 59 pivotally supported at 60 on the side wall of the machine, and having a roller 61 operatively mounted thereon and in operative contact with a cam 62 secured upon the power shaft 1.

The cam 62 is of such formation as to cause the movement, through the linkage described, of the stop members 36 upwardly into position for abutment by the bottles in the chambers 11 in synchronism with the lifting of the loading plate 26 for discharge of the bottles therefrom into the chambers 11, and also to permit the return of the stop members 36 to lowermost position, effected by the spring 63, so that the bottles in the holder chambers are permitted to slide into the bottle pockets 9 while the latter remain in position to receive them.

It is desirable after the rinsing of the bottles to divert, from the solution tanks provided in the machine, the rinse water carrying substances removed from the bottles which flows therefrom at the completion of the rinsing. To this end, a receiving pan 64 (Fig. 3) is provided beneath the lower ends of the bottle chambers in the bottle holder 10 and suitably supported upon the frame structure of the washing machine, as by brackets 65. The bottles are held within the chambers for a period after the cutting off of the spraying jets, the rinse water draining therefrom into the pan 64 and, by suitable connections with an outlet opening 66, outwardly of the machine.

Means are provided in association with the bottle stop and spraying mechanism for automatically stopping the operation of the machine in the event that a bottle should fail to pass fully within the conveyor bottle pockets when released from the rinsing chambers in the bottle holder. If, for any reason, a bottle should be arrested in its passage into the

socket so that it remained in engagement with the rinsing mechanism, it is obvious that further movement of the conveyor would result in damage to the machine. The safety stop mechanism provided comprises a rocking bar 67, positioned over the space between the bottle holder and the conveyor bottle pockets by means of a pair of brackets 68 secured to the bar and operatively supporting the latter. The brackets 68 are constructed in the form of bell cranks, intermediately pivoted on studs 69 mounted in the respective side walls of the machine. One arm of each bell crank supports the bar, the other arm having a bifurcated end portion carrying a cross pin 70 which is engaged in a longitudinally arranged slot formed in the end of a crank 71 extending into the bifurcated portion of the crank 68 and rigidly secured to the shaft 53. The operating connections just described effect the lowering of the bar 67 toward the bottle stop and spraying members 36 as the latter are swung into upward position for the abutment of bottles admitted to the rinsing chambers.

It will here be obvious that if a bottle or any portion remains in the space between the holder and the bottle pockets, or protrudes from the latter sufficiently far to engage any of the rinsing mechanism, the bottle will be engaged by the bar 67 and effect the stoppage of the movement of the shaft 53. The result of stopping the rotation of the shaft 53 is to release the main driving clutch through which power is transmitted to the machine as a whole, as fully illustrated and described in Patent No. 1,775,003, granted September 2, 1930, upon the application of George F. Soelch, and of which the crank 72 (see Fig. 2) and the pivoted bar 73 are component parts. The space between the holder and the pockets being clear, the bar 67 swings into downward position while the bottles are retained in the rinsing chamber, and with the reverse movement of the stop members the bar 67 is elevated to permit the free passage of the bottles when released from the chambers 11.

The upper ends of the rinsing chambers in the bottle holder are provided with pivoted enclosures or doors 74, which are pushed upward by the entering bottles and rest thereupon while the latter are within the rinsing chambers receiving the spray from the rinsing jet. If, however, a bottle has not been placed on the loading plate 26 before any one or more of the chambers, so that with the elevation of the loading plate no bottle is discharged into the chamber, the door 74 remains in downward position and receives the spray discharged from the rinsing jet, thus preventing the spray from being thrown outwardly of the chamber through the upper end.

I claim as my invention:

1. In a bottle washing machine having a series of conveyor pockets supported for movement successively into position to receive bottles, a pre-rinsing device comprising a bottle holder supported in substantial alignment with said pockets successively when in receiving position, a stop member positioned between said holder and the path of movement of said pockets, said stop member being operable into position for abutment by a bottle in said holder for retention of said bottle therein and being operable into position to permit the passage of said bottle from said holder into one of said pockets, and spray means operable into position before the mouth of said bottle while said bottle is being retained in said holder, said spray means being adapted to discharge rinsing fluid within said bottle when in such position. 70 75 80 85

2. In a bottle washing machine having a series of conveyor pockets supported for movement successively into position to receive bottles, a pre-rinsing device comprising a bottle holder supported in inclined position in spaced endward relation to said pockets successively when in receiving position, a stop member positioned between said holder and said pockets, said stop member being operable into and out of position for abutment by a bottle in said holder, and spray means carried by said stop member adapted to spray fluid upon said bottle while in said holder. 90 95

3. In a bottle washing machine having a series of conveyor pockets supported for movement successively into position to receive bottles, a pre-rinsing device comprising a bottle holder supported in inclined position in spaced endward relation to said pockets successively when in receiving position, a stop member positioned between said holder and said pockets, said stop member being operable into and out of position for abutment by a bottle in said holder, spray means having a discharge orifice in said stop member adapted to spray fluid upon said bottle while in said holder, and means controlling said spray means for operation of said spray only when said stop member is in position for abutment by a bottle. 100 105 110 115

4. In combination with a conveyor having pockets arranged for successive movement into position to receive bottles, a pre-rinse device comprising a bottle holder mounted in endwardly spaced relation to the path of movement of said pockets, one end of said holder being pivotally supported and the other end of said holder being adjustably supported for alignment with said pockets when in bottle receiving position, a stop member operatively mounted between said holder and said bottle pockets, said stop member being operable into position for abutment by a bottle in said holder for retention of the same 120 125 130

therein and into position to permit passage of said bottle from said holder into one of said pockets, and spray means carried by said stop member for rinsing said bottle while 5 retained in said holder.

5. In combination with a conveyor having pockets arranged for successive movement into position to receive bottles, a pre-rinse device comprising an inclined bottle holder 10 supported in substantial alinement with said pockets when in receiving position, said bottle holder having laterally enclosed chambers formed therein for the reception of bottles, a series of stop members positioned between said chambers and said pockets, said stop members being operable into and out of position for abutment by a bottle in said holder, spray means adapted to spray fluid upon said bottles while in said chambers, and 15 a door pivotally supported in each of said chambers, said doors being arranged to drop by gravity into closed position when no bottle is present in a chamber whereby the spray discharged into said chamber is prevented 20 from passing outwardly therefrom.

6. In a device of the class described, a bottle holder having inclined chambers formed therein with open ends, a pair of axially alined pivoted brackets operatively supporting adjacent to the lower ends of said chambers, a tubular bar supported on said brackets in eccentric relation to the axis thereof, a series of stop members mounted on said tubular bar, each of said stop members having a 25 face extending toward the adjacent ends of said chambers respectively, each of said stop members having a passage communicating with the interior of said tubular bar and terminating outwardly in a spray orifice formed 30 in the face of said stop member, said stop members being swingable by said brackets and tubular bar across the adjacent ends of said chambers for abutment by bottles positioned therein with said spray orifices in register with the mouths of said bottles, and means for supplying spray fluid to said tubular bar.

7. In combination with a conveyor having pockets arranged for successive movement into position to receive bottles, a pre-rinse device comprising a bottle holder supported in inclined position in spaced endward relation to said pockets when in receiving position, a stop member operatively supported 55 between said holder and said pockets, said stop member being operable into and out of position for abutment by a bottle in said holder, spray means carried by said stop member operable upon a bottle retained in 60 said holder, and means mounted on said stop member providing a slideway for said bottle between said holder and said pockets when said stop member is moved out of position of abutment with said bottle.

8. In a device of the class described, a bot-

tle holder having a chamber with open ends, a tubular shaft positioned adjacent one end of said chamber, a hollow bracket mounted on said shaft having inward communication with said shaft, a tubular bar supported on 70 said bracket in eccentric relation to the axis of said shaft and having communication with the interior of said bracket, a stop member mounted on said bar and having a passage communicating with the interior of said 75 tubular bar, said passage terminating outwardly in a spray orifice formed in the face of said stop member adjacent said chamber, said stop member being swingable about the axis of said shaft across the adjacent end of 80 said chamber for abutment by a bottle positioned therein with said spray orifice in register with the mouth of said bottle, and means for supplying spray fluid to said tubular shaft.

9. In a bottle washing machine having a series of conveyor pockets supported for movement successively into position to receive bottles, a pre-rinsing device comprising a bottle holder supported in inclined position 85 in spaced endward relation to said pockets successively when in receiving position, said holder being pivotally supported at one end and having an adjustable support for its end adjacent the path of said pockets for 90 alignment of said holder with said pockets in receiving position, a stop member positioned between said holder and said pockets, said stop member being operable into and out of position for abutment by a bottle in 95 said holder, and spray means mounted upon said stop member adapted to spray fluid upon said bottle while in said holder.

10. In a bottle washing machine having a series of conveyor pockets supported for 100 movement successively into position to receive bottles, a pre-rinsing device comprising a bottle holder supported in inclined position in spaced endward relation to said pockets successively when in receiving position, 105 said holder having a laterally enclosed chamber for the passage of bottles endwardly therethrough, a stop member positioned between said holder and said pockets adjacent one end of said chamber, said stop member being operable into and out of position for abutment by a bottle in said chamber, spray means carried by said stop member adapted to spray fluid upon said bottle while in said chamber, and a swinging door mounted in 110 the opposite end of said chamber, said door being movable out of the path of a bottle entering said chamber and adapted to swing into closing relation to the end of said chamber when no bottle is present, whereby said 115 spray is intercepted by said door.

In testimony whereof, I have hereunto affixed my signature.
